UNITED STATES PATENT OFFICE.

CHARLES O. JUNGE, OF PITTSBURGH, PENNSYLVANIA, ASSIGNEE OF ONE-HALF TO
EDWARD E. RIECK, OF PITTSBURGH, PENNSYLVANIA.

REFRIGERATOR-BODY FOR VEHICLES.

1,400,880.

Specification of Letters Patent. Patented Dec. 20, 1921.

Application filed October 11, 1920. Serial No. 416,037.

To all whom it may concern:

Be it known that I, CHARLES O. JUNGE, a citizen of the United States, and residing in the city of Pittsburgh, in the county of Allegheny and State of Pennsylvania, have invented or discovered new, useful, and Improved Refrigerator-Bodies for Vehicles, of which the following is a specification.

My invention consists in certain new and useful improvements in refrigerator bodies for vehicles intended for the wholesale delivery of ice cream and other frozen products.

In the case of vehicles of this character, 15 the load or burden usually consists of the frozen products packed in cans and other containers together with a supply of refrigerants such as broken ice and salt for preserving the products en route, for packing 20 the products as they are delivered, and for repacking such products as may have been left over in the customer's possession from the previous delivery.

It is important that the vehicle may be 25 loaded at the plant as quickly as possible, and it is also important that the various units in the load be readily accessible with a minimum of handling the rest of the load. It is also important that the product be kept 30 at the proper temperature while en route. It is further important to keep the weight of the body down as much as possible to reduce the dead load.

For the accomplishment of these, and 35 other, advantageous results, I provide a vehicle body having a storage compartment for holding and refrigerating the products, whose roof is formed of a pan or shallow container adapted to be filled with broken 40 ice and salt and having walls formed of vertically disposed tanks, adapted to be filled with broken ice and also to receive the drip from the aforementioned pan, said tanks being provided at their lower ends 45 with drainage means. A suitable closure is provided for the top of the ice pan, which enclosure is, at least in part, removable to permit loading of said pan. Doors are provided in the side walls of said body for access to 50 said compartment.

The body is also provided, preferably at 55 the rear of the product storage compartment above referred to, with an ice storage compartment to which loading access is had through the roof or top of the body, and

from which the broken ice is removed at the rear of the vehicle body by means of a rearwardly extending and downwardly inclined chute whose discharge end is preferably inclosed by a new and improved end gate structure. 60

I also provide, preferably in the extreme rear of the body, a salt compartment into which the salt is loaded at the top and which is provided with an internal, inclined baffle 65 adapted to direct the salt in a pile on the bottom of the compartment within easy reach of an access hole in the back end of the vehicle through which a scoop may be inserted. 70

I also provide an open top apartment, preferably above the rear portion of the ice storage compartment, to receive empty containers collected from customers, or, when necessary, an extra supply of ice. 75

Other novel features of construction and arrangement of parts will appear from the following description.

In the accompanying drawings, which are, however, merely intended to illustrate practical embodiments of the principles of my invention without limiting the scope of the latter to the construction shown, Figure 1 is a side elevation of a motor truck body to which the principles of my invention are applied; Fig. 2 is a longitudinal section of the same, the roof door of the product compartment being shown folded back and that of the ice compartment swung into a vertical position; Fig. 3 is a plan view, with the roof of product compartment omitted and the pan partially broken away to show the parts; Fig. 4 is a broken rear elevation of the body, showing the means for gaining access to the supplies of broken ice and salt; Fig. 5 is a perspective showing one of the vertical ice tanks which form the front and rear walls of the product compartment; Fig. 6 is a side elevation showing my improvements embodied in a wagon or animal drawn truck body; and Fig. 7 is a section of the same along the line VII—VII in Fig. 6. 90 95 100 105

The following is a detailed description of the drawings, reference being first had to Figs. 1 to 5, inclusive.

The body is of the inclosed type and comprises, generally, a product storage compartment A; an ice storage compartment B, preferably next in the rear, and a salt storage compartment C, preferably in the rear 110

of the ice compartment B and at the rear of the body. I also prefer to provide an open top compartment D, preferably in front of the upper portion of the salt compartment 5 C and extending down into the ice storage compartment B. The compartment D may be used to hold empty containers as they are collected from customers, or, in case an extra supply of ice is required, as for Saturday 10 deliveries or during excessively hot weather, for an additional supply of ice.

The side and front walls of the vehicle body may be of ordinary construction for refrigerator bodies; for instance outer and 15 inner layers or thicknesses of wood with an interlining of cork or some other suitable insulation against heat.

The compartment A is provided with a sheet metal floor covering 1 which has its 20 side and front edges flanged up at 2 against the front and side walls of the vehicle. The floor 3 of the vehicle extends under the whole of the compartment A but under the compartments B and C the floor is interrupted 25 along the horizontal center of the body to provide space for the rearwardly inclined chute 4 which extends from the front of the compartment B to the rear of the body. The metal floor covering 1 is continued 30 to the rear of the vehicle to form the floor of the chute 4, and the chute is provided with sides 5 which extend up to and support the chute from the floor beams. The floor of the compartment A is preferably 35 slightly inclined toward the rear so as to drain into the chute 4.

The front and rear walls of the compartment A are formed by vertically disposed tanks E, preferably made of heavy, galvanized 40 sheet metal. The backs 6 of said tanks are flat and extend up to fit the double pitch of the roof. The fronts 7 of said tanks are formed of vertically corrugated or fluted metal to provide an increased radiating surface. The ends 8 of the tanks are flat and 45 may be formed by flanging the front and back sheets and riveting or soldering the flanges together. The front tank rests against the front wall of the vehicle body, 50 while the rear tank separates the compartments A and B. In the rear of the upper back wall of the rear tank E, a strut or partial partition 9 connects the body sides having its top edge double pitched to support 55 the roof doors. Vertical cleats 10 secured to the body sides may also be provided to hold the tanks in proper position and alinement.

The interiors of the tanks are braced by 60 vertically disposed bars 11, and in the bottoms of the tanks I fix the inverted trough shaped metal members 12 having parallel sides, and which support the ice in the tanks but permit the meltage to run down along 65 the interiors of the corrugations in the front

walls. The bottoms of the tanks are stepped in the shallow metal troughs or boxes 13, closed at their ends, and which rest on the floor of the compartment, and thus support the tanks. Said boxes are provided with 70 drain pipes 14 which depend through holes in the body floor and are threaded to receive the traps 14a which may be removed to permit the tanks to be flushed out with a hose to carry off sand and other foreign material 75 deposited from the broken ice and salt.

F represents a pan or shallow container horizontally disposed to form the top of the compartment A. Said container is preferably made of heavy galvanized iron. It is 80 provided with shallow sides 15 having outwardly turned top flanges 16 which rest upon the top edges of the side walls of the body and are secured in place by nails or screws. The pan is also provided with angle 85 joist or braces 17 to support the bottom 18 of the pan, said joist having bent ends which are secured by bolts or screws to the body sides. The pan spans the space between the two tanks E and at its ends the 90 bottom 18 is flanged downwardly within said tanks and riveted to their front walls 7 which have horizontal top edges to support the tank. The side walls 15 of the tank extend over the interior of the tank. 95

The pan F is intended to be loaded with broken ice and salt, the drippings from which run down into the tanks E.

The compartment A is also preferably provided with a horizontally disposed shelf 100 19, which is preferably of metal and also preferably perforated. The ends of said shelf are supported by horizontal cleats 20 attached to the side walls of the body, while the center of said shelf is supported by an 105 angular bracket 21, whose horizontal leg is bolted to the front wall of the adjacent tank E while its vertical leg is bolted to one of the joist 17.

Access is gained to the compartment A 110 by means of doors 22 in the side walls of the body at the lower centers of the compartments.

The rear wall of the tank E which forms the partition between the compartments A 115 and B is preferably provided at its bottom with a sliding door 23 so that in case the ice stored in the compartment B is exhausted, an auxiliary supply may be taken from the interior of the tank through said 120 door.

The compartment D which is formed from space borrowed from the upper rear portion of the compartment B is formed by the partition 24, which forms the front wall of the 125 salt compartment C, the horizontal floor 25 which is supported by the side walls of the body, and the front partition 26 extending down to said floor 25. The top of the partition 26, as is also the front wall of the 130

body, is given the proper pitch to carry the roof structure.

The compartments A and B are provided with permanent roof portions 27 at the sides 5 and pairs of top doors 28 which meet and lap in the center to form the ridge and are supported by the front wall of the body, the partition 9 and the partition 26. If desired the compartments C and D may be provided 10 with similar roof structures but usually these are omitted.

The salt compartment C is provided with a floor 29 which bridges the chute 4, and above said floor an inclined baffle 30 extending 15 from one side of the compartment, preferably the right side, toward the other side so that the salt will keep sliding down said baffle and pile up on the floor below the lower end of the baffle. Toward the right 20 side of the body and below the baffle 30, the rear wall of the body is provided with an aperture 31 through which a scoop may be inserted to take out salt. Thus the aperture 25 may be left open for easy access without possibility of spilling out the salt.

32 represents the end gate which closes the rear or discharge end of the chute 4. The bottom of said gate is hinged to the bottom edge of said chute and 33 are supplemental side plates attached to the ends of 30 said gate and moving against the sides of said chute so that when the gate is open, a box with closed ends is formed from which the ice sliding down the chute may be 35 shoveled as needed. 34 is an iron whose ends are horizontal and attached to the bottom of the vehicle body while its intermediate portion forms a rectangular saddle with its bottom bearing against and secured to the 40 under side of the chute to support the same, while its vertical legs extend up outside of the side plates 33 of the end gate 32 forming slots for said side plates to move in. Said side plates are provided with projections 45 35 which are adapted to engage said iron and thus limit the opening of said end gate. 36 is a fastening to hold the end gate in its closed position.

In Figs. 6 and 7 I show my invention developed in connection with a wagon or animal-drawn truck in which case the driver's cab usually extends back into space borrowed from the compartment A and said compartment is extended under the driver's 55 seat, as at 37. In this case the front ice tank E does not extend down to the floor but is supported by cleats 38 attached to the body walls so as to give access to the space 37 under the driver's seat.

60 In the case of animal-drawn vehicles, to save weight, I use a padded canvas cover instead of the wooden doored roof shown in connection with the motor truck body.

Thus said cover is made in two parts; a 65 front part G which forms the roof of the

compartment A, and the rear part H which forms the roof of compartment B. The cover G is permanently secured at its front to the front wall of the body and is detachably secured in position over the compartment A as by lashings 39 so that the cover can be rolled or folded forwardly for loading ice into the tanks E and ice and salt into the pan F. Similarly the cover H is permanently attached to the top of the partition 26 and detachably held in place as by lashings 39 so that said cover may be rolled or folded back to permit ice to be loaded into the compartment B.

The covers are centrally supported by the 80 horizontal ridge pole or beam 40 which runs from the front wall of the body across the partition 9 to the partition 26.

At the start of a trip the tanks E are loaded with cracked ice and the pan F with 85 ice and salt. Ice is also loaded into the compartment B, and if required also into the compartment D, and salt is loaded into the compartment C. The product packed in suitable containers is loaded into the compartment A. When product is delivered to a customer, the driver opens one of the doors 22 and pulls out the proper container. He then shuts the door. If the container is not already packed in a tub, he proceeds 90 to pack the container in a tub with ice and salt taken from the rear of the body. The container is already in a tub but owing to meltage requires repacking, the driver drains off the water from the tub and re-packs the later with ice and salt.

The ordinary practice in ice cream delivery is to use an open top wagon and piling the broken ice about the tubs in which the containers are packed. This entails a great 105 wastage of ice and it is hard to deliver the products in good condition. It is also inconvenient and requires much lifting and re-handling of the containers and tubs.

My improved vehicle body is very convenient to work with as the supplies of ice and salt are readily gotten at and handled, and the product can be readily and quickly removed when needed. The body may also be loaded with product and refrigerants 110 very quickly. A minimum amount of refrigerants are required to keep the product in a well frozen condition en route, and such refrigerants are so disposed as to take up but little valuable space in the body. The 115 body is therefore much lighter than other vehicle bodies in which an attempt is made to refrigerate the product during its transportation.

In my improved body the rear ice tank 120 E not only refrigerates the contents of the compartment A, but it also retards the melting of the supply of ice carried in the compartment B.

I recommend that, as the filled containers 130

are received from the compartment A, empty containers with their lids in place be substituted in said compartment, thus occupying space which would otherwise be occupied 5 by warm air from outside.

While my vehicle body has been especially designed for the transportation of frozen food products, such as ice cream, it is quite evident that it may be advantageously used 10 for transporting any character of substances, materials or articles which require a low temperature for preservation.

Although, for the sake of clearness, I have minutely described the embodiment of the 15 principles of my invention, as the same are illustrated in the accompanying drawings, I do not wish to limit myself thereby, but claim broadly:—

1. In a vehicle body for the transportation 20 of frozen products, a product compartment having walls comprised of vertically disposed ice tanks, means spaced above the bottom of said tanks for the support of their solid contents, trough members in 25 which said tanks are stepped, and drainage means for said trough members.

2. In a vehicle body for the transportation 30 of frozen products, a product compartment having walls comprised of vertically disposed ice tanks; said ice tanks having vertically corrugated front walls, horizontal floors in said tanks spaced above the bottom of the latter for the support of their solid contents, the interiors of said corrugations forming passages past said floors for 35 the escape of water from melting of the ice, and troughs into which the lower ends of the tanks are stepped.

3. In a vehicle body for the transporta-

tion of frozen products, the combination of 40 a product compartment in the front of the body, an ice compartment in the rear of said product compartment, a rearwardly extending and downwardly inclined discharge 45 chute leading from the floor of said ice compartment, and a salt compartment in the rear of said ice compartment, said chute extending under said salt compartment to the rear end of the vehicle.

4. In a vehicle body for the transportation 50 of frozen products, the combination of a product compartment in the front of said body, an ice compartment in the rear of said product compartment, a rearwardly extending and downwardly inclined discharge 55 chute in the central bottom of said ice compartment and extending to the rear of said body, and the floor of said product compartment being inclined rearwardly to drain into said chute.

5. In a vehicle body for the transportation 60 of frozen products, the combination of a product compartment in the front of said body, an ice compartment in the rear of said product compartment, a rearwardly 65 extending and downwardly inclined discharge chute in the floor of said ice compartment leading to the back of said body, a salt compartment in the rear of said ice compartment, said chute extending under 70 said salt compartment to the rear end of said vehicle, and an open top storage compartment in front of said salt compartment and extending down into said ice compartment.

Signed at Pittsburgh, Pa., this 2nd day 75 of Oct., 1920.

CHARLES O. JUNGE.
